Attest:

UNITED STATES PATENT OFFICE.

ROBERT BEARDSLEY, OF CHICAGO, ILLINOIS.

DESIGN FOR A LAMP SHADE OR SIMILAR ARTICLE.

Continuation of application Serial No. D. 21,331, filed March 25, 1927. This application filed October 17, 1927. Serial No. 23,770. Term of patent 3½ years.

To all whom it may concern:

Be it known that I, ROBERT BEARDSLEY, a citizen of the United States, residing at Chicago, in the county of Cook and State of Illinois, have invented a new, original, and ornamental Design for a Lamp Shade or Similar Article, of which the following is a specification, reference being had to the accompanying drawing, forming a part thereof, this application being a continuation of my pending application filed March 25, 1927, Serial No. 21,331.

Fig. 1 is a plan view of a lamp shade, showing my new design; and

Fig. 2 is a side elevation of the shade.

The dominant feature of my new design is the provision of two bands adjacent the upper and lower edges of the lamp shade or similar article and a plurality of rivets projecting from the bands. The bands are of a different color than the rivets or the body of the lamp shade or similar article.

I claim:

The ornamental design for a lamp shade or similar article, as shown and described.

ROBERT BEARDSLEY.
